UNITED STATES PATENT OFFICE.

JOHN C. AMUNDSON, OF CROSBY, MINNESOTA.

PHOTO-NEGATIVE DRIER.

1,111,938.

Specification of Letters Patent. Patented Sept. 29, 1914.

Application filed April 29, 1914. Serial No. 835,225.

To all whom it may concern:

Be it known that I, JOHN C. AMUNDSON, a citizen of the United States, residing at Crosby, in the county of Crow Wing and 5 State of Minnesota, have invented certain new and useful Improvements in Photo-Negative Driers, of which the following is a specification, reference being had to the accompanying drawings.

10 This invention relates to photo negative driers.

The emulsion on negatives is very sensitive and soft after developing and fixing, and will often in hot and sultry weather 15 melt and therefore either entirely ruin the negative, or render it unfit for use. In order to obviate this, it is necessary to subject the prepared negative to a draft of air, but heretofore the difficulty has been, so far 20 as is known, that where a negative is placed in a natural draft, without some artificial protection, it is liable to become injured by dust, and where artificial means, such as an electric fan, is employed to create a draft 25 the expense will prove a serious handicap, and also the difficulty in rural districts of obtaining electric power for driving the fan will, in many instances, preclude the installation of such means.

30 The object of the present invention is to provide a photo negative drier which shall be of such construction as to permit of its being readily manufactured by a person of ordinary mechanical skill, and which in operation will not only be thoroughly effective 35 in generating a natural draft through the drier, but will also protect the contained negatives from danger of becoming damaged by dust and other impurities.

40 With the above and other objects in view, as will appear as the nature of the invention is better understood, the same consists, generally stated, in a photo negative drier embodying a chamber or casing arranged to 45 maintain the negatives placed therein in spaced relation, and to provide a tortuous passage therebetween whereby to insure the most effective action upon the sensitized surface of the air current passing through 50 the chamber. The chamber or casing is provided with dust proof top, bottom and sides, and with one open end, the other end being closed and having combined with it a section of stove pipe that is designed to be 55 inserted within the stove pipe opening of

the chimney, whereby at all times to insure a draft or suction through the casing. In order to permit the passage of air through the casing without the entrance of dust, there is combined with the structure a shield 60 in the nature of a length of cloth, such as cheese cloth, which is securely fastened around the open end and sides of the casing and is readily removed therefrom for the purpose of laundering.

65 The structure as a whole is a cheap grade of stock, and will require no expensive fittings to render it thoroughly effective in accomplishing the results designed.

In the accompanying drawings forming a 70 part of this specification, and in which like characters of reference designate corresponding parts: Figure 1 is a view in perspective of the apparatus showing the parts closed; Fig. 2 is a similar view with the 75 parts open to display the interior and exterior mechanism thereof; Fig. 3 is a plan view, part in section of the apparatus; Fig. 4 is a perspective detail view of a holder with the improvement employed in conjunction with the apparatus.

80 The apparatus comprises a chamber consisting of a top 1, a bottom 2, two sides 3 and 4 and an end consisting of two heads 5 and 6. The bottom is approximately solid, 85 while the top is provided with a rectangular opening adapted to be closed by a hinged door or cover 7 which will fit within the opening of the top in such manner as to secure a dust proof juncture between the parts. As shown, the top and bottom are built up 90 of short pieces of stock, this for the purpose of cheapness, but it is to be understood that a particular manner of constructing these parts is not essential, as any preferred mode may be employed. The sides, adjacent their ends, have secured to them vertical cleats 8, 9 and 10, the same arrangement being observed on both sides, and the bottom is reinforced by transverse cleats 12.

95 The inner walls of the two sides are provided with vertical grooves or channels 13, that are arranged in break-joint order and are designed to receive the ends of the negatives N and hold them properly spaced apart and in vertical position, the chamber being of such width that the negatives will not reach entirely across the same so that 105 a tortuous passage will be formed between the positioned negatives that will be effective 110

in causing air passing through the structure to be equally applied to each of the negatives, thus to insure effective drying thereof.

The heads at the top and bottom of the casing at the open end thereof are preferably rounded, although this is not essential, and the heads or ends 5 and 6 are each provided with circular openings 15 and 16, respectively, and the latter opening is engaged by one end of a length of stove pipe P, the other end of which is designed to be inserted in the flue hole of a chimney.

In order to permit the passage of currents of air through the chamber or casing and at the same time preclude the entrance of dust or any other substance that would cause deterioration of the negatives, a shield 16 is provided, the same consisting of a length of cheese cloth, the opposed edges of which are provided with marginal pockets, in which are arranged draw strings 17 which serve to secure the shield firmly around the casing and to the upper and lower edges thereof.

In order to permit the apparatus to be used when drying plates of different sizes, frames or holders may be employed, which will be of a size to admit of their being inserted from the open top of the casing, one of these frames being shown in Fig. 4, and which consists of a bottom 18 and sides 19 and 20, the latter being provided with vertical grooves or channels 21 corresponding to like parts 13 in the walls of the casing.

In the use of the apparatus, the same is positioned with the flue or pipe P disposed within the chimney flue, and when charged or loaded with plates, the cover 7 is closed and the shield 16 placed in position, and thereupon a natural draft will be forced through the chamber due to the updraft of the chimney and this will operate in a rapid and thoroughly effective manner to accomplish the drying of the plates in the minimum of time.

It will be obvious that this apparatus is more particularly designed for use by photographers in rural districts where stove pipe flues are in use, but it will be evident that it could be quickly attached for use by photographers in cities, as it would be an easy matter to provide an opening in the wall for the reception of the pipe, and connect the latter with a wooden flue extending above the roof.

The improvements herein described are simple in character, will be found thoroughly efficient for the purposes designed and will coact in the presentation of a practical, dur-

able and easily constructed photo-negative 60 drier.

Having thus described my invention, what I claim is:

1. A photo negative drier comprising a chamber having sides provided with vertical 65 grooves or channels, a hinged top and a solid bottom, one end of the chamber being open, heads secured to the other end and provided with an opening, a flue arranged in one of the heads, and a fabric shield detachably 70 secured around the open end and sides of the chamber.

2. A photo-negative drier comprising a chamber having sides provided with vertical 75 grooves or channels, a hinged top and a solid bottom, one end of the chamber being open, and a flue in communication with the chamber through the opposite end.

3. A photo-negative drier comprising a chamber having sides provided with vertical 80 grooves or channels, a hinged top and a solid bottom, one end of the chamber being open, heads secured to the opposite end and provided with an opening, and a flue arranged in one of the heads.

4. A photo-negative drier comprising a chamber having sides provided with vertical 85 grooves or channels, a top provided with an opening, means for closing said opening in the top, a solid bottom, one end of the chamber being open, a flue in communication with the chamber through the opposite end, and a fabric shield detachably disposed across the open end of the chamber.

5. A photo-negative drier comprising a 95 chamber having sides provided with vertical grooves or channels, said sides being spaced apart a distance in excess of the width of a negative, a hinged top and a solid bottom, one end of the chamber being open, and a 100 flue in communication with the chamber through the opposite end.

6. A photo-negative drier comprising a chamber having sides provided with vertical 105 grooves or channels, the grooves or channels in one side being positioned intermediate the grooves or channels of the opposite side, a hinged top and a solid bottom, one end of the chamber being open, and a flue in communication with the chamber through 110 the opposite end.

In testimony whereof I hereunto affix my signature in the presence of two witnesses.

JOHN C. AMUNDSON.
